UNITED STATES PATENT OFFICE.

ISAAC L. RHEUTAN, OF RICHMOND, VIRGINIA, ASSIGNOR TO UNION ENVELOPE COMPANY, OF RICHMOND, VIRGINIA.

ENVELOP-MACHINE.

1,194,784.

Specification of Letters Patent. Patented Aug. 15, 1916.

Application filed June 12, 1915. Serial No. 33,719.

To all whom it may concern:

Be it known that I, ISAAC L. RHEUTAN, a citizen of the United States, residing at Richmond, in the county of Henrico and 5 State of Virginia, have invented certain new and useful Improvements in Envelop-Machines; and I do hereby declare the following to be a full, clear, and exact description of the invention, such as will enable others 10 skilled in the art to which it appertains to make and use the same.

My invention consists in the novel features hereinafter described with reference to the accompanying drawings, in which I 15 have illustrated the same, and the said invention is fully disclosed in the following specification and claims.

Referring to the drawings, Figure 1 represents a top plan view of an envelop machine showing my improved mechanism for applying a transparent patch to an envelop window. Fig. 2 is a front view of the same. Fig. 3 is an end view. Fig. 4 is a longitudinal vertical sectional view of the patch 25 conveyer and transparent paper guide. Fig. 5 is a top plan view of the same. Fig. 6 is a detail, showing an end view of the conveyer and paper guide and a side view of the paper shears. Figs. 7 and 8 are a top 30 plan and end view, respectively of the tilting plate forming a portion of the transparent paper guide. Fig. 9 is a view of the envelop blank showing the adhesive applied thereto. Fig. 10 is a detail taken on line 10—10 of 35 Fig. 1. Fig. 11 is a detail showing the cam for operating the transparent paper shears.

My invention relates to mechanism for manufacturing what are known in the trade as "outlook envelopes". This style of envelop, which has lately come into extensive use, is exemplified in the patent to Callahan, dated June 10, 1902, No. 701,840. This patent discloses an envelop having an elongated aperture in the body portion thereof 45 covered with transparent paper, so that the address upon the inclosure will be exhibited through said transparency and the necessity of addressing the envelop will be obviated.

The object of my present invention is to 50 provide means for applying the transparent patch to the opening of the envelop, and I have shown in the accompanying drawings the mechanism embodying my invention, as applied to an envelop machine of the 55 well known "Schmidt" type. In this type

of envelop machine, the envelop blank is taken from the pile by the envelop blank gummers and elevated. A carriage is then moved beneath the elevated blank and the blank stripped from said gummers by a 60 stripping plate and deposited on the carriage which then conveys the gummed blank to the folding box where the envelop is completed.

My attachment is designed to apply the 65 transparent patch to the envelop blank just after it has been stripped from the gummers by the stripping plate and deposited on the carriage and before the carriage is moved toward the folding box.

My improved mechanism for applying the transparency comprises means for applying adhesive to the edges of the envelop opening simultaneously with the application of adhesive to the envelop flaps, means for conveying a previously cut transparent patch to proper position over the envelop window, means for bringing said transparency into engagement with the adhesive surrounding said opening, and means for pressing said transparency upon the same simultaneously with the folding of the envelop.

In the accompanying drawings, I have shown only such portions of an envelop machine as are necessary for a complete understanding of my invention.

Referring to the drawings, 1 is a portion of the lower frame or stand, 2 is the table and 3 is the arch or upper frame work of an envelop machine; 4 is an envelop blank supporting or feeding table, which is adapted to be intermittently elevated by any suitable means to move upwardly at predetermined intervals, in the usual way.

5 represents a pile of envelop blanks supported by the table 4 and 6 designates a reciprocating rod arranged above said blanks and carrying flap gummers 7, and a window or opening gummer 8, the latter being adapted to apply adhesive to the edges 9 of the envelop blank window 10, as shown in Fig. 9. A stripper plate 11 is also arranged above the blanks and is apertured to permit the passage of the gummers 7 and 8, and a conveyer 12 is adapted to be moved beneath said stripper plate at predetermined times to convey the blanks to the folding box 13 after they have been stripped from said gummers by the stripping plate.

An adhesive container 14 is mounted upon

the table 2 and is divided into a number of adhesive receptacles 15 for different classes of gum, by partitions 16. A gum feeding roller 17 is loosely mounted in each of said receptacles 15. Tracks 18 are suitably supported by a stationary portion of the upper frame work above the table 2 and a carriage 19 having a roller 20 is adapted to be reciprocated on said tracks by rods 21 connected by suitable mechanism (not shown) to the driving mechanism.

The operation of the device thus far described, is as follows: The roller 20 receiving adhesive from the rollers 17 is moved toward the right by the rods 21 to apply adhesive to the lower surfaces of the gummers 7 and 8, and the rod 6 is then moved downwardly until the gummers contact with the uppermost blank of the pile 5 to apply adhesive to the flaps of said blank and to the edges of the window opening of the same. The rod 6 is then raised and the gummers carry the topmost blank to the stripper plate 11, where it is stripped off and deposited upon the conveyer 12, which, as the blank was elevated has been moved beneath the same. It is at this time that the patch applying mechanism comes into play and this I shall now proceed to describe.

Mounted on an arm 22, standing upon the table 2 is a roll 23, containing a continuous strip 24 of transparent paper, which passes between feeding rolls 25, that are connected for joint movement by the gears 26 and are continuously driven by a sprocket chain 27 from the drive shaft 28, said chain passing around gears 29 and 30, one on one of the rolls 25 and one on the drive shaft 28, respectively. Said strip 24 passes downwardly from the feed rolls 25 to a guide 31, then across to a guide 32, which gives the strip a half turn so that it will pass to a strip conveyer 33 in proper alinement. Mounted in standards 34 upon the table 2 are a plurality of intermittently operated feeding rolls 35, which are geared for joint movement by gears 36. The lower one of the rolls 35 is rigidly mounted upon a spindle 37, which carries at one end a gear 38. A shaft 39 is also mounted upon the table 2 and is provided with a rigidly mounted mutilated gear 40 which meshes with the gear 38 and operates the same. The shaft 39 is driven by a sprocket chain 41 which engages a gear 42 upon said shaft and a gear 43 upon a spindle 44 that carries the lower one of the feed rolls 25.

From the foregoing, it will be seen that as the drive shaft 28 moves the sprocket chain 27 and through it the feed rolls 25 and the spindle 44, the sprocket chain 41 will continuously turn the shaft 39 and its gear 40. The mutilated gear 40 will impart an intermittent motion to the gear 38 and through this train of mechanism, the strip 24 of

transparent paper which is engaged by the rolls 35 will be fed forward a sufficient distance to constitute one patch, upon each complete cycle of operation.

Mounted upon supports 45 and extending from the stripping plate 11 to the intermittent feed rolls 35, are guides 46 in which the strip conveyer 33 is mounted for reciprocating movement. The end of these guides 46 near the feed rolls 35 is cut away on their under sides to accommodate a tilting guide plate 47, which is only connected to said guides by screws 48 located near one end of said plate 47, so that its opposite end is capable of a slight movement vertically.

Attached to one end of the strip conveyer 33 is a link 49 which is pivotally connected to an arm 50, rigidly mounted on a rock shaft 51. A gear 52 upon the rock shaft is oscillated by a rack 53, which slides in bearings 54 and is reciprocated vertically by means of a cam 55 upon the drive shaft 28. A roller 56 upon the lower end of the rack 53 rides upon the cam 55 and is kept in constant engagement with the same by a spring 57, one of the ends of which engage one of the bearings 54 and the other end of which engages a collar 58 provided upon the rack 53. From the mechanism just described, it will be seen that upon each revolution of the drive shaft 28, the conveyer 33 will be reciprocated once. At this point it may be well to mention that the upper one of the intermittent feed rollers 35 is not integral from one end to the other, but consists of two parts 35^a and 35^b with a space between them for the passage of the conveyer 33 and these parts 35^a and 35^b are each mounted upon a link 35^c which is pivotally connected at 35^a to the uprights 34, so that the upper roll 35 may be raised to thread the transparent strip between them. The transparent strip, after being threaded through the rollers 35 passes through the ways 59 in the tilting plate 47 and in the guides 46.

A movable shear knife 60, for severing the transparent strip into desired lengths for patches, is pivotally connected at one end to one of the guides 46 and is provided at its other end with a roller 61 which travels on a cam 62 carried by the shaft 39 so that each time the shaft 39 is rotated, the knife 60 will be moved up against a stationary knife 63 and sever the transparent strip. Each time the knife 60 is raised it also elevates the free end of the tilting plate 47 and prevents the free end of the uncut transparent strip from curling up or moving out of alinement. When the knife is lowered, the tilting plate 47 drops back into normal position and places the uncut transparent strip in perfect alinement to continue on the ways 59 in the guides 46.

The conveyer 33 carries at its free end a gripping mechanism comprising a jaw 64

80

120

125

130

forming part of the conveyer, and a jaw 65 which is pivotally mounted on a spindle 66 provided on said conveyer. The jaw 65 is normally held out of engagement with the 5 jaw 64 by means of a spring pressed bolt 67, which engages cam faces 68 and 69 on said jaw 65. Forming part of said jaw 65 is a tail piece 70 which when the conveyer 33 is moved toward the right, engages a stop 71 and causes the jaw 65 to be rocked and close the jaws 64 and 65 to engage the patch of transparent paper which has previously been 10 cut by the knife 60. When the tail piece 70 is depressed to close the gripping jaws the bolt 67 engages the cam face 69 of the jaw 65 and serves to maintain the jaw 65 in its closed position. As the conveyer is moved toward the left and approaches its extreme 15 left position, a stop 72 which is carried by the adhesive container 14, engages the tail 20 piece 70 and opens the jaw 65 to release the patch of transparent paper and allow the same to drop into position upon the previously gummed window 10 of the envelop 25 blank which rests upon the conveyer 12. When the jaw 65 is opened by the stop 72, it is prevented from accidentally closing, by the bolt 67 engaging its cam face 68.

In order that the gummed envelop blank 30 may be held in proper position on the conveyer 12, and that the transparent patch will properly aline over the envelop window and be held temporarily in position until it is pressed by the plunger 73 of the folding 35 mechanism, I have provided an air blast mechanism, which consists of a pump 74 comprising a piston equipped cylinder actuated by an eccentric 75. Three pipes 76, 77 and 78 each having an automatic valve 79, 40 extend from the pump up to and along the arch 3, from which they pass to the stripping plate 11. The pipe 76 terminates in an opening in the stripping plate 11 directly over the point marked X, in Fig. 9, so that 45 a blast of air directed on the spot X will maintain the envelop blank upon the conveyer 12. The pipes 77 and 78 pass along the edges of the stripping plate, where the window gummer operates and these pipes 50 are provided along those edges with a series of small apertures to permit a line of air to be directed on the edges of the transparent patch which overlap the edges of the blank window 10, and thereby cause said 55 patch to adhere to the envelop blank. After the patch has been applied the conveyer 12 conveys the blank to the folding box, where the transparency is pressed into firm engagement with the blank and the envelop folded. 60 What I claim and desire to secure by Letters Patent is:—

1. In an envelop machine, the combination with means for applying gum to an envelop blank in close proximity to an opening in 65 the same, of means located directly beneath

the gumming means for applying a patch to the envelop blank to cover the opening, means for simultaneously folding the blank and pressing the patch upon the same, and means for uninterruptedly feeding the 70 patched blank from the patch applying means to the folding and pressing means.

2. In an envelop machine, the combination with means for simultaneously applying gum to the flaps and around an opening in 75 an envelop blank, of means located directly beneath the gumming means for applying a patch to the envelop blank to cover said opening, means for simultaneously folding the blank and pressing the patch upon the 80 same, and means for feeding the patched blank from the patch applying means to the folding and pressing means.

3. In an envelop machine, the combination with means for applying gum to an envelop 85 blank in close proximity to an opening in the same, of an air blast mechanism for applying a patch to the envelop blank to cover the opening, means for simultaneously folding the blank and pressing the patch 90 upon the same, and means for feeding the patched blank from the patch applying means to the folding and pressing means.

4. In an envelop machine, the combination of a feeding table, for supporting a pile of 95 envelop blanks, a reciprocating gumming die for applying gum around an opening in the uppermost blank in said pile, means located directly beneath the gumming die for applying a patch to the envelop blank to 100 cover said opening, means for simultaneously folding the blank and pressing the patch upon the same, and means for feeding the patched blank from the patch applying means to the folding and pressing means.

5. In an envelop machine, the combination with a feeding table for supporting a pile of envelop blanks, of a stripping plate arranged above said table, a reciprocating 110 gumming die for applying gum around an opening in the uppermost blank in said pile, an air blast mechanism for directing air through said stripping plate for applying a patch to the envelop blank to cover said opening, means for simultaneously folding 115 the blank and pressing the patch upon the same, and means for feeding the patched blank from the patch applying means to the folding and pressing means.

6. The combination with mechanism for 120 gumming and folding an envelop blank, of means for applying a patch to the envelop blank to cover an opening in the same, said patch applying means comprising means for applying gum around the envelop opening, 125 a support for a roll containing a continuous strip of transparent paper, means for intermittently feeding the paper from said roll, means for severing said strip into patches of predetermined length, means for convey- 130

ing a single patch to a position over the opening in the envelop blank, and an air blast mechanism for directing air upon the overlapping surfaces of the patch and blank.

7. The combination with mechanism for gumming and folding an envelop blank, of means for applying a patch to the envelop blank to cover an opening in the same, said patch applying means comprising mechanism for applying gum around the opening in the blank, a support for a roll containing a continuous strip of transparent paper, means for intermittently feeding the paper from the roll, guides into which said strip is fed by said feeding means, a tilting plate forming part of said guides, a conveyer adapted to be reciprocated in said guides, a reciprocating knife pivotally mounted on said guides and adapted to operate said tilting plate each time the knife is reciprocated to sever the transparent strip into patches of a predetermined length, said conveyer being adapted to convey a single patch into a position over the opening in the envelop blank, and means for bringing said patch into engagement with the adhesive surrounding said opening.

8. The combination with mechanism for gumming and folding an envelop blank, of means for applying a patch to the envelop blank to cover an opening in the same, said patch applying means comprising mechanism for applying gum around the opening in the blank, a support for a roll containing a continuous strip of transparent paper, means for intermittently feeding the paper from the roll, guides into which said strip is fed by said feeding means, a tilting plate forming part of said guides, a conveyer adapted to be reciprocated in said guides, a reciprocating knife pivotally mounted on said guides and adapted to operate said tilting plate each time the knife is reciprocated to sever the transparent strip into patches of a predetermined length, said conveyer being adapted to convey a single patch into a position over the opening in the envelop blank, and an air blast mechanism for applying a patch to the envelop blank to cover said opening.

9. The combination with mechanism for gumming an envelop blank around an opening therein, of mechanism for folding the flaps of said blank and means for feeding the blank from the gumming mechanism to the flap folding mechanism, a feed table arranged beneath said gumming mechanism for supporting a pile of envelop blanks, and mechanism interposed between the gumming mechanism and feed table for applying a patch to the blank to cover the opening therein while said blank rests directly beneath the gumming means.

10. A machine for making window en-

velops comprising means for simultaneously applying gum to the flaps and around the opening in an envelop blank, means for folding said blank, means for conveying the blank from the gumming mechanism to the folding mechanism, and means for applying a transparent patch to said blank to cover the opening therein while said blank rests directly beneath the gumming means, said patch applying means comprising means for severing a transparent strip into patches, means for conveying a patch to the envelop blank, and an air blast mechanism for applying said patch to cover the opening in the blank.

11. A machine for making window envelopes comprising means for simultaneously applying gum to the flaps and around the opening in an envelop blank, means for folding said blank, means for conveying the blank from the gumming to the folding mechanism, and means for applying a transparent patch to said blank to cover the opening therein, said patch applying means comprising a support for a roll containing a continuous strip of transparent paper, means for intermittently feeding said strip from said roll, guides for said strip, severing means for said strip arranged in said guides, a patch conveyer for conveying said severed patch from the guides to a position over the opening in the envelop blank, and an air blast mechanism for bringing said patch into engagement with the adhesive surrounding said opening.

12. A machine for making window envelopes comprising a frame, a feed table for supporting a pile of envelop blanks, a reciprocating gumming die for applying gum to the flaps and around an opening in the uppermost blank in said pile, an apertured stripping plate arranged between said feed table and said gumming die, a blank folding mechanism, a conveyer for conveying the blanks from the gumming to the folding mechanism, means for conveying a transparent patch to the envelop blank upon said conveyer, said stripping plate having air apertures arranged directly above the edges of the envelop opening and of the sealing flap of the blank, and means for forcing a blast of air through said air openings to retain the blank upon the blank conveyer and bring the transparent patch into engagement with the adhesive surrounding the opening in the blank.

13. A machine for making window envelopes comprising a frame, a drive shaft mounted in said frame and provided with an eccentric, means for simultaneously gumming the flaps and applying gum around the opening in an envelop blank, means for folding the blank, means for conveying the blank from the gumming to the folding mechanism, a stripping plate for stripping

the gummed blank from the gumming means and depositing the same upon the conveyer, means for bringing a transparent patch into position to register over said blank opening upon said conveyer, said stripping plate having air apertures arranged directly above the edges of the envelop blank opening, a pump provided on said frame and operated by said eccentric, 10 and pipes provided between said pump and said air apertures.

14. A machine for making window envelops comprising means for supporting a pile of envelop blanks, reciprocating means 15 for simultaneously applying gum to the flaps and around an opening in the uppermost blank and elevating the same, a conveyer adapted to be moved beneath the gummed blank when the latter is elevated, 20 means for stripping said gummed blank from the gummers to permit the same to drop onto said conveyer, means for applying a patch to said blank while it is resting on said conveyer beneath the gummers, and 25 means for simultaneously folding the blank and pressing the patch upon the same, said conveyer being adapted to carry the blank from the patch applying means to the folding and pressing mechanism.

15. A machine for making window envelops comprising a frame, a feed table carried by said frame for supporting a pile of envelop blanks provided with openings, 30 gumming mechanism for simultaneously applying gum to the flaps and around the opening in the uppermost blank, said gummers being arranged above the feed table and being mounted in the frame for reciprocating movement, folding mechanism 35 also carried by said frame, a blank conveyer arranged between said gumming and folding mechanisms, a support for a roll of transparent paper containing a continuous strip carried by said frame, intermittently operated feed rollers and guides for 40 said strip mounted upon said frame, a knife for shearing said strip into patches of predetermined length pivotally mounted on said guides and provided with a roller, a 45 cam engaging said knife roller for operating said knife, a conveyer for conveying a patch to a position over the envelop blank opening, and means for applying the patch to 50 the blank to cover said opening.

16. In an envelop machine, the combina-

tion with means for applying gum to an envelop blank in close proximity to an opening in the same, of means for applying a patch to the envelop blank to cover the opening, while said blank rests directly beneath said gumming means, means for simultaneously folding the blank and pressing the patch upon the same, and means for feeding the patched blank from the patch applying means to the folding and 65 pressing means.

17. In an envelop machine, the combination with means for applying gum to the flaps of an envelop blank, of means for applying gum to said blank in close proximity 70 to an opening in the same simultaneously with the gumming of the flap, means for applying a patch to the envelop blank to cover said opening, while said blank rests directly beneath the gumming mechanism, 75 means for simultaneously folding the blank and pressing the patch upon the same, and means for feeding the patched blank from the patch applying means to the folding and pressing means.

18. In an envelop machine, the combination of a feeding table, for supporting a pile of envelop blanks, a reciprocating gumming die for applying gum to the uppermost blank in said pile, in close proximity to an 80 opening in the same, means for applying a patch to the envelop blank to cover said opening while the blank rests beneath said gumming die, means for simultaneously folding the blank and pressing the patch 85 upon the same, and means for feeding the patched blank from the patch applying means to the folding and pressing means.

19. An envelop machine comprising means for applying gum around an opening in an 90 envelop blank, means for simultaneously folding the blank and pressing a patch upon the same, means for conveying said blank from the gumming means to the folding and pressing means, and means for applying 95 a patch to the envelop blank to cover the opening in the same while said blank rests on the conveying means directly beneath the gumming means.

In testimony whereof I affix my signature, in the presence of two witnesses.

ISAAC L. RIEUTAN.
